ALONZO T. BOON AND LUCIEN MILLS, OF GALESBURG, ILLINOIS.**

Letters Patent No. 101,423, dated April 5, 1870.

IMPROVED FLOUR-SIFTER, COLEANDER, AND STRAINER.

The Schedule referred to in these Letters Patent and making part of the same

To all whom it may concern:

Be it known that we, ALONZO T. BOON and LUCIEN MILLS, of the city of Galesburg, in the county of Knox and State of Illinois, have invented a new and improved Combined Sieve, Colander, and Strainer for Flour, Fruit, and Vegetables; and we do hereby declare that the following is a full, clear, and exact description of the construction and operation of the same, reference being had to the accompanying drawings making a part of this specification, in which—

Figure 1 is a plan view.

Figure 2 is a side elevation.

Figure 3 is a section as indicated by the line $x-x$ of fig. 1.

Like letters in the different figures of the drawings indicate like parts.

Our invention consists of a concave receptacle or frame with stationary or removable wire legs, in combination with one or more movable sieves, colanders, and strainers, of a hemispherical shape, and a spiral rubber stirrer attached to a wire crank-shaft supported by a removable spider or wire frame, so that said sieves, colanders, and strainers may be used either for sifting flour, straining the juice of fruit, or separating the pulp from vegetables, being easily adjusted and removed for the substitution of the one for the other in their respective uses.

To enable others skilled in the art to make and use our invention, we will proceed to describe its construction and operation.

A is the concave receptacle or frame, the top *a* being of tin, of about two and a half inches in width, and having three wire legs, *b*, soldered onto the outside thereof, the legs being so bent as to converge toward a point in a line with the center of the receptacle, so as to form the shape of the latter, the bottom ends being bent out enough to support the receptacle or utensil properly, and fastened by a piece of wire, *c*, wound around in the turn or bend of the legs.

The legs may be made removable, if preferable, for convenience in packing for transportation, by inserting them in sockets *d*, one of which only is shown in fig. 2.

B is a hemispherical-shaped sieve, which is intended to fit loosely but snugly within the concave receptacle, and rest upon the legs so as to be easily removable and allow of the substitution of a strainer or colander in lieu of the sieve, when desired to use either for fruit or vegetables, and we design to have the wire of the sieves or strainers turned or plated, especially for fruit or jellies, though the sieve for flour may also be turned if desired.

C is the stirrer, provided with rubber or other flexible material, which is placed between the jaws or sides of a tin clamp, of a spiral shape, the clamp conforming to the shape of the hemispherical sieve. The rubber, instead of being riveted to the clamp as here-

tofore, is held by indenting either side of the clamp, so as to press the tin slightly into the rubber wherever the indentation is made; thus, in the event of the rubber wearing out, as will likely be the case, a person can very easily slip it out and put another piece in its place by inserting the blade of a knife between the rubber and the sides of the clamp, and loosening the clamp from it, but where the rubber is riveted this cannot be done well.

Attached centrally to the clamp is the vertical wire crank-shaft *f*, the ends of the clamp being secured by a wire brace, *g*, wound with one or two turns around the shaft.

The crank-shaft *f* is supported by the spider or wire frame above, having three wire arms, *h*, attached to a tin tube, *D*, in which the shaft is passed through and has its bearing, the wire arms resting upon the rim of the concave receptacle, and strengthened by angular braces of tin *E*.

The wire arms have coiled spring ends *i*, so that they may easily be pressed or sprung over the rim of the receptacle to hold the spider or wire frame firmly in place, and may as easily be released from the rim when desiring to remove the spider or wire frame in the changing of the sieves.

The spider or wire frame may be constructed entirely of wire, if preferable. In that event, the angular tin braces would be dispensed with, the arms and braces then being formed of one piece of wire with the braces bent angularly, the ends of each arm and brace being fastened to circular plates of tin soldered on around the top and bottom of shaft-tube.

We are aware that removable sieves of a flat form have been used, but they are objectionable for the reason they do not present the same area of sifting or straining-surface as a hemispherical one does, consequently the work cannot be performed as effectually and speedily as with a hemispherical sieve, though we are also aware that a hemispherical sieve has been used before, but being stationary it could only be used for sifting flour; therefore, it is not as desirable and convenient a utensil for general use as this, where it is proposed to make the hemispherical sieve removable, so that one of another kind, or a strainer or a colander, may be substituted in its place with facility.

We are aware that a removable cast-iron spider or frame has been used, but it is believed, by making it and the shaft of wire, and having the ends of the arms of the spider coiled or bent, in the manner described, we are enabled to cheapen the cost of its construction, besides rendering it more easily to be fastened and removed from the rim of the receptacle.

Operation.

By turning the crank the rubber stirrer is rotated, which thoroughly stirs the flour or meal and presses

* Assignors to themselves & G. L. Olmstead Jr.

it against the sides of, and rapidly sifts it through the sieve; and by removing the sieve and inserting the strainer by the same process, the juice of fruit is strained, and by removing the strainer and inserting the colander the pulp may be separated from vegetables, such as potatoes, tomatoes, pumpkins, &c., without the inconvenience of manipulating them, as is required by the ordinary process.

Having thus fully described our invention, What we claim therein as new, and desire to secure by Letters Patent, is—

1. A concave receptacle or frame, A, with stationary or removable wire legs b, constructed as described, in combination with removable hemispherical sieves, colanders, and strainers, substantially as and for the purposes set forth.

2. The removable wire frame, consisting of wire arms h, with coiled spring ends i, tube D, and angular braces E, for supporting the shaft of a rotary stirrer or scraper, in combination with a stationary or removable sieve and concave receptacle, substantially as set forth.

As evidence that we claim the foregoing as our invention, we have hereunto set our names in the presence of two witnesses.

ALONZO T. BOON.
LUCIEN MILLS.
